MOISTENING DEVICE FOR POSTAGE STAMPS, ENVELOPES AND THE LIKE

Leone Montalcini, Turin, Italy

Application April 3, 1953, Serial No. 346,556

7 Claims. (Cl. 118—264)

This invention relates to moistening devices and more particularly, to moistening devices including a liquid reservoir.

In the course of daily office routine it is often necessary to moisten one's fingers or the back of postage stamps, envelopes etc. It is amongst the objects of the present invention to provide a device which permits such wetting operations to be performed in an efficient and convenient manner.

With the above objects in view the present invention mainly consists in a moistening device, in combination, a receptacle provided with a wall portion and having an open top, a cover having a rim portion forming an opening and provided with a flange engaging the wall portion of the receptacle, and guide shanks extending downwardly from the rim portion into the receptacle, a perforated plate member in the receptacle having guide slots disposed adjacent its edge corresponding to the downwardly extending guide shanks for being guided by the downwardly extending guide shanks, elastic supporting means within the receptacle pressing the perforated plate member against the rim portion of the cover, and an absorbent material member supported by the plate member.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a perspective view of an embodiment of the device of the present invention;

Fig. 2 is a sectional view of the device shown in Fig. 1 taken on line 2—2 of Fig. 1 in the direction of the arrows; and

Fig. 3 is a sectional plan view of the device taken on line 3—3 of Fig. 2 in the direction of the arrows.

Referring now to the drawing and particularly to Fig. 2 thereof, the moistening device of the present invention includes a cylindrical receptacle 1 having an open upper portion which is exteriorly threaded for engagement with annular cover member 8 mounted upon the open end of receptacle 1. Cover member 8 essentially consists of a circular band or rim having an interiorly threaded flange 2 depending from its outer periphery for engagement with the upper portion of cylinder 1 and a plurality of guide shanks 7 depending from a cylindrical flange 10 extending downwardly from its inner periphery.

Vertically positioned coil spring 3, housed within receptacle 1, engages the bottom wall of the latter and the underside of a disc 4 to maintain disc 4, having a plurality of perforations 5 formed therein, in an elevated position within receptacle 1. Disc 4 is provided with a plurality of arcuate slots 6, angularly distributed along an imaginary circle near the periphery of disc 4, through which arcuate guide shanks 7, depending from cylindrical

2

flange 10, respectively extend. It can be seen that by this arrangement, the said disc is movable only in a vertical direction, horizontal motion being prevented by guide shanks 7.

As will be seen from the drawing, spring 3 urges disc 4 against the bottom edge of cylindrical flange 10, flange 10 and disc 4 thereby defining an open chamber wherein an absorbent sponge 9 is placed.

It is evident that whenever a downward pressure is applied to sponge 9, the perforated disc is also caused to move downwardly causing the water, retained in cylinder 1, to be contacted by sponge 9 thereby causing the moistening of the sponge. As soon as the pressure is released spring 3 moves the disc and the sponge back to their original elevated position.

When it is desired to fill cylinder 1 with water, the water may be introduced into the cylinder simply by being poured through perforations 5. If it is desired to gain access into the interior of receptacle 1, cover member 8 is simply unscrewed and removed from the open end of the said receptacle.

I claim:

1. In a moistening device, in combination, a receptacle provided with a wall portion and having an open top; a cover having a rim portion forming an opening and provided with a flange engaging the wall portion of the receptacle, and guide shanks extending downwardly from said rim portion into the receptacle; a perforated plate member in said receptacle having guide slots disposed

adjacent its edge corresponding to said downwardly extending guide shanks for being guided by the said downwardly extending guide shanks; elastic supporting means within said receptacle pressing said perforated plate member against said rim portion of said cover; and an absorbent material member supported by said plate member.

2. In a moistening device in combination, an open receptacle provided with a wall portion; a cover composed of a rim portion provided with an inwardly extending inner flange, an outer flange engaging the wall portion of the receptacle, and guide shanks extending downwardly from said inner flange of the cover and in parallel relationship to the walls of the receptacle; a perforated plate member in said receptacle having guide slots corresponding to said downwardly extending guide shanks for being guided by same; elastic supporting means within said receptacle pressing said plate member against said inner flange of said cover to define an open chamber therewith; and an absorbent material member arranged in said open chamber and supported by said plate member.

3. In a moistening device in combination, an open receptacle provided with a wall portion; a cover composed of a rim portion provided with an inwardly extending inner flange, an outer flange engaging the wall portion of the receptacle, and guide shanks extending downwardly from said inner flange of the cover and in parallel relationship to the walls of the receptacle and in spaced relationship therewith; a perforated plate member in said receptacle having guide slots corresponding to said downwardly extending guide shanks for being guided by same;

elastic supporting means within said receptacle pressing said plate member against said inner flange of said cover to define an open chamber therewith; and an absorbent material member arranged in said open chamber and supported by said plate member.

4. In a moistening device, in combination, an open receptacle provided with a wall portion and an outwardly threaded neck portion; a cover composed of a rim portion provided with an inwardly extending inner flange and an outer inwardly threaded flange meshing with said outwardly threaded neck portion and guide shanks extending downwardly from said inner flange of the cover and in parallel relationship to the wall of the receptacle; a per-

forated plate member in said receptacle having guide slots corresponding to said downwardly extending guide shanks for being guided by the same; elastic supporting means within said receptacle pressing said plate member against said inner flange of said cover to define an open chamber therewith; and an absorbent material arranged in said open chamber supported by said plate member.

5. In a moistening device, in combination, an open receptacle provided with a wall portion and an outwardly threaded neck portion; a cover composed of a rim portion provided with an inwardly extending inner flange and an outer inwardly threaded flange meshing with said outwardly threaded neck portion and guide shanks extending downwardly from said inner flange of the cover and in parallel relationship to the wall of the receptacle; a perforated plate member in said receptacle having guide slots corresponding to said downwardly extending guide shanks for being guided by the same; a metal spring within said receptacle pressing said plate member against said inner flange of said cover to define an open chamber therewith; and an absorbent material arranged in said open chamber supported by said plate member.

6. In a moistening device, in combination, an open circular receptacle provided with a wall portion and an outwardly threaded neck portion; a circular cover composed of a rim portion provided with an inwardly extending inner flange and an outer inwardly threaded flange meshing with said outwardly threaded neck portion and guide shanks extending downwardly from said inner flange of the cover and in parallel relationship to the wall of the receptacle; a perforated plate member in said

10 receptacle having guide slots corresponding to said downwardly extending guide shanks for being guided by the same; a metal spring within said receptacle pressing said plate member against said inner flange of said cover to define an open chamber therewith; and an absorbent material arranged in said open chamber supported by said plate member.

15 7. In a moistening device, in combination, an open circular receptacle provided with a wall portion and an outwardly threaded neck portion; a circular cover composed of a rim portion provided with an inwardly extending inner flange and an outer inwardly threaded flange meshing with said outwardly threaded neck portion and guide shanks extending downwardly from said inner flange of the cover and in parallel relationship to the wall of the receptacle; a perforated plate member in said receptacle having apertures corresponding to said downwardly extending guide shanks for being guided by the same; a metal spring within said receptacle pressing said plate member against said inner flange of said cover to define an open chamber therewith; and an absorbent material arranged in said open chamber supported by said plate member.
